VEHICLE HOLDING STRUCTURE

James J. Pelouch, Cleveland, Ohio, assignor, by
mesne assignments, to Harold C. Schott, Cleve-
land, Ohio

Application March 7, 1950, Serial No. 148,060

10 Claims. (Cl. 254—89)

1
This invention relates to vehicle lifting hoists and especially to a structure for preventing sidewise movement of a vehicle resting on the hoist. It has been found that many times the vehicle will start to slide or move sidewise while it is on a vehicle lifting hoist. Generally this sidewise movement results from rocking or shaking of the vehicle while it is on the hoist, such, for example, as during lubrication or greasing of the vehicle. Many persons working around lifting hoists have become frightened at the sliding of the vehicle and feel that the hoist is dangerous to use since the vehicle is usually raised several feet above the ground level.

An object of the invention is to eliminate the danger of a vehicle sliding off a vehicle lifting hoist.

Another object of the invention is to provide a vehicle lifting hoist with outwardly urged pins for preventing sidewise movement of a vehicle resting thereon.

A further object of the invention is to provide the vehicle engagement structure with a plurality of pins independently urged by spring means in an upwardly direction to hold a vehicle being lifted on the vehicle engagement structure.

Other objects and a fuller understanding of this invention may be had by referring to the following description and claims, taken in conjunction with the accompanying drawings in which:

Figure 1 is a picture view of a vehicle lifting hoist;

Figure 2 is an enlarged top view;

Figure 3 is an enlarged side view of the cross-saddle on the front lift post of Figure 1; and

Figure 4 is a sectional view along the line 4—4 of Figure 2.

The vehicle lifting hoist illustrated in Figure 1 of my drawings is a two-post lift having a front lift post 10 and a back lift post 11. It is understood that in describing the present invention, reference is made to the front lift post 10 of the particular lift illustrated by way of example only. The front lift post 10 is termed such since it generally lifts the front end of a vehicle and it is understood that the present invention may be used on vehicle lifting hoists of other designs and constructions.

In the present disclosure wherein the invention is illustrated in connection with the front lift post by way of example, the front lift post 10 has a cross-saddle 12 mounted thereon. The cross-saddle 12 is the vehicle engagement structure which comes in contact with the vehicle resting on the lift.

2
The vehicle engagement structure, which in this instance is the cross-saddle 12, comprises a support member 14 in the form of a channel member having first and second ends 15 and 16, respectively. The first and second ends 15 and 16 constitute substantially upright channel members having upper pads 17 and 18, respectively, welded thereto at 30 and 31, being along the outside surface 41 of the channel members, see Figures 3 and 4. The upper pads 17 and 18 may also be welded at 35 and 36 to the inside flanges of the channel members. The upper pads 17 and 18 are the parts on which the vehicle being lifted rests. These upper pads 17 and 18 of the first and second ends 15 and 16 of the cross-saddle 12 are spaced apart whereby the wheel structure of the vehicle rests on the pads. Newer model vehicles which have knee-action generally do not have the old type axle which extended clear across between the wheels. Thus when the vehicle is resting on the hoist, the knee-action next adjacent one wheel would rest on one upper pad and the knee-action next adjacent the other wheel would rest on the other upper pad. During greasing of the vehicle, many times, the operator shakes the vehicle to insure grease entering all of the joints. This shaking has a tendency to cause the vehicle to slide sidewise and sometimes drop off from upper pads 17 and 18 respectively, whereby the vehicle becomes damaged or the operator injured.

To prevent sidewise movement of the vehicle, the cross-saddle 12 has been provided with holding pins 19. These holding pins 19 are extendable upwardly through holes 20 in the upper pads 17. The holding pins 19 are urged in an upward direction through the holes 20 in the upper pads by urging means such, for example, as spring 21 or other resilient material.

In the present instance, lower pads or plates 22 and 23 have been mounted on the first and second ends 15 and 16 respectively, directly below the upper pads 17 and 18, respectively, and spaced therefrom. In the specific embodiment of the invention, the plate 22 is constructed of two parts 22A and 22B. Likewise, the plate 23 is constructed of two parts 23A and 23B. The parts 22A and 23A are welded respectively at 32 and 33 to the outside surface 41 of the channel members. The parts 22B and 23B are welded respectively at 42 and 43 to the inside flanges of the channel members, see Figure 2. Spacer plates 37 may be employed to additionally fasten the plates 22A and 22B to the upper plate 17 by welding same thereto by weld 38. Likewise, spacer plates 39

may be employed to additionally fasten the plates 23A and 23B to the upper plate 18 by welding same thereto by weld 40. The springs 21 are positioned between the upper and lower pads and abut against the lower pad to urge the holding pins upwardly. Each holding pin or plunger 19 independently urged upwardly by its independently operating spring 21. Although other suitable means for urging the pins upwardly may be used, it has been found advisable to provide the plunger or holding pins 19 with shoulders 24 facing the lower pad and against which the coil spring abuts. To prevent the coil spring 21 from urging respective holding pins 19 completely out of the upper pads, the holding pins 19 have been extended through openings 25 in the lower pads. Snap rings 26 snapped on to the lower end of the holding pins or plungers 19 at a point below the lower pads limit upward movement of the plunger or holding pins 19.

When a vehicle is being lifted by lifting hoists, the plungers or holding pins 19 are urged upwardly against or on the side of parts of the vehicle. Thus one holding pin may be depressed by the weight of the vehicle since a part thereof is immediately over the depressed holding pin and at the same time another of the holding pins may extend upwardly along side the same or another part of the vehicle. If a holding pin is depressed by a part of the vehicle and the vehicle moves slightly in any direction whereby that pin is released from said part, that pin will immediately snap upwardly along side of or next adjacent to that part. Many times this snapping of the pins upwardly makes noise whereby the operator of the hoist knows that the pins are in holding position. If a part of the vehicle resting on the upper pad has an opening or a depression therein, a pin may snap upwardly into or be positioned in such opening or depression. The holding pin or plunger 19 may be any projection or other upwardly movable member which may be extended upwardly from the engagement structure to prevent sidewise slippage or movement of the vehicle in any direction while it is resting on the vehicle engagement structure of the lifting hoist. With the vehicle hoists equipped with plungers or holding pins, the same as or similar to those illustrated or described in the present invention, there is little danger of the vehicle moving sidewise or sliding off the vehicle lift hoist. It is understood that many other vehicle hoists may be equipped with upwardly urged plungers which will prevent slipping sidewise of the vehicle and thus hold it safely.

Although this invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

I claim:

1. In a vehicle lifting hoist having a lift post with a vehicle engagement structure thereon, the provision of said vehicle engagement structure having, an upper pad and a lower pad spaced apart, said upper pad having a plurality of openings therethrough, a plurality of pins in said openings, and spring means urging said pins upwardly through said upper pad to hold a vehicle being lifted on said vehicle engagement structure.

2. In a vehicle lifting hoist having a lift post with a vehicle engagement structure thereon, the provision of said vehicle engagement structure having, an upper pad and a lower pad spaced apart, at least said upper pad having a plurality of openings therethrough, a plurality of pins in said openings, and spring means located between said pads and urging said pins upwardly through said upper pad to hold a vehicle being lifted on said vehicle engagement structure.

3. In a vehicle lifting hoist having a lift post with a cross-saddle thereon, the provision of said cross-saddle comprising, first and second ends, at least said first end having an upper pad and a lower pad spaced apart, said upper pad having a plurality of openings therethrough, a plurality of pins in said openings, and spring means urging said pins upwardly through said upper pad to hold a vehicle being lifted on the upper pad.

15 4. In a vehicle lifting hoist having a lift post with a cross-saddle thereon, the provision of said cross-saddle comprising, first and second ends, at least said first end having an upper pad and a lower pad spaced apart, at least said upper pad having a plurality of openings therethrough, a plurality of pins in said openings, and spring means urging said pins upwardly through said upper pad to hold a vehicle being lifted on the upper pad.

20 5. In a vehicle lifting hoist having a lift post with a cross-saddle thereon, the provision of said cross-saddle comprising, first and second ends, at least said first end having an upper pad and a lower pad spaced apart, said upper pad having a plurality of openings therethrough, a plurality of pins in said openings, and spring means located between said pads and urging said pins upwardly through said upper pad to hold a vehicle being lifted on the upper pad.

25 6. In a vehicle lifting hoist having a lift post with a cross-saddle thereon, the provision of said cross-saddle comprising, first and second ends spaced apart, each of said ends having an upper pad and a lower pad spaced apart, said upper pad having a plurality of openings therethrough, a plurality of pins in said openings, and spring means urging said pins upwardly through said upper pad to hold a vehicle being lifted on the upper pads.

30 7. In a vehicle lifting hoist having a lift post with a cross-saddle thereon, the provision of said cross-saddle comprising, first and second ends spaced apart, each of said ends having an upper pad and a lower pad spaced apart, at least said upper pad having a plurality of openings therethrough, a plurality of pins in said openings, and spring means located between said pads and urging said pins upwardly through said upper pad to hold a vehicle being lifted on the upper pads.

40 8. In a vehicle lifting hoist having a lift post with a cross-saddle thereon, the provision of said cross-saddle comprising, first and second ends spaced apart, each of said ends having an upper pad and a lower pad spaced apart, at least said upper pad having a plurality of openings therethrough, a plurality of pins in said openings, and spring means located between said pads and urging said pins upwardly through said upper pad to hold a vehicle being lifted on the upper pads.

45 9. In a vehicle lifting hoist having a lift post with a cross-saddle thereon, the provision of said cross-saddle comprising, first and second ends spaced apart, each of said ends having an upper pad and a lower pad spaced apart, at least said upper pad having a plurality of openings therethrough, a plurality of pins in said openings, and spring means located between said pads and urging said pins upwardly through said upper pad to hold a vehicle being lifted on the upper pads.

50 10. In a vehicle lifting hoist having a lift post with a cross-saddle thereon, the provision of said cross-saddle comprising, first and second ends spaced apart, each of said ends having an upper pad and a lower pad spaced apart, at least said upper pad having a plurality of openings therethrough, a plurality of pins in said openings, and spring means located between said pads and urging said pins upwardly through said upper pad to hold a vehicle being lifted on the upper pads.

55 11. In a vehicle lifting hoist having a lift post with a cross-saddle thereon, the provision of said cross-saddle comprising, first and second ends spaced apart, each of said ends having an upper pad and a lower pad spaced apart, at least said upper pad having a plurality of openings therethrough, a plurality of pins in said openings, and spring means located between said pads and urging said pins upwardly through said upper pad to hold a vehicle being lifted on the upper pads.

60 12. In a vehicle lifting hoist having a lift post with a cross-saddle thereon, the provision of said cross-saddle comprising, first and second ends spaced apart, each of said ends having an upper pad and a lower pad spaced apart, at least said upper pad having a plurality of openings therethrough, a plurality of pins in said openings, and spring means located between said pads and urging said pins upwardly through said upper pad to hold a vehicle being lifted on the upper pads.

65 13. In a vehicle lifting hoist having a lift post with a cross-saddle thereon, the provision of said cross-saddle comprising, first and second ends spaced apart, each of said ends having an upper pad and a lower pad spaced apart, at least said upper pad having a plurality of openings therethrough, a plurality of pins in said openings, and spring means located between said pads and urging said pins upwardly through said upper pad to hold a vehicle being lifted on the upper pads.

70 14. In a vehicle lifting hoist having a lift post with a cross-saddle thereon, the provision of said cross-saddle comprising, first and second ends spaced apart, each of said ends having an upper pad and a lower pad spaced apart, at least said upper pad having a plurality of openings therethrough, a plurality of pins in said openings, and spring means located between said pads and urging said pins upwardly through said upper pad to hold a vehicle being lifted on the upper pads.

75 15. In a vehicle lifting hoist having a lift post with a cross-saddle thereon, the provision of said cross-saddle comprising, first and second ends spaced apart, each of said ends having an upper pad and a lower pad spaced apart, at least said upper pad having a plurality of openings therethrough, a plurality of pins in said openings, and spring means located between said pads and urging said pins upwardly through said upper pad to hold a vehicle being lifted on the upper pads.

provision of said vehicle engagement structure having, an upper pad and a lower pad spaced apart, said upper pad having a plurality of openings therethrough, a plurality of projections in said openings, and means urging said projections upwardly through said upper pad to hold a vehicle being lifted on said vehicle engagement structure.

10. In a vehicle lifting hoist having a lift post with a cross-saddle thereon, the provision of said cross-saddle comprising, first and second ends

spaced apart, each of said ends having an upper pad and a lower pad spaced apart, at least said upper pad having a plurality of openings therethrough, a plurality of projections in said openings and means located between said pads and urging said projections upwardly through said upper pad to hold a vehicle being lifted on the upper pads.
